UNITED STATES PATENT OFFICE.

CHARLES W. CRAM, OF CHICKASAW, ALABAMA.

OIL-BAFFLE PLATE.

Application filed November 19, 1924. Serial No. 750,873.

To all whom it may concern:

Be it known that I, CHARLES W. CRAM, a citizen of the United States, residing at Chickasaw, in the county of Mobile and State of Alabama, have invented new and useful Improvements in Oil-Baffle Plates, of which the following is a specification.

My invention is an oil baffle plate for internal combustion engine pistons and its principal object is to provide an attachment for pistons which will prevent pumping of oil into the combustion chamber as well as the upper end of the piston and thereby eliminate all of the disadvantages incident to such pumping of the oil.

My invention also contemplates an attachment which can be readily associated with any internal combustion engine piston which will eliminate wasting of the oil, fouling of the spark plugs and all other disadvantages incident to oil entering the grooves of the piston and cylinders.

With the preceding and other objects and advantages in mind, the invention consists in the novel combination of elements, construction and arrangement of parts and operations to be hereinafter specifically referred to, claimed, and illustrated in the accompanying drawings, wherein:

Figure 1 is a vertical sectional view of a piston constructed in accordance with my invention.

Figure 2 is a similar view taken at right angles to Figure 1.

Figure 3 is a transverse sectional view of the piston.

Figure 4 is a sectional view of the attachment, and

Figure 5 is a detail view of parts of the invention.

The invention as reduced to practice, comprises a circular plate 5 having a depending annular flange 6 which with the plate 5 is positioned in the lower end of the piston 45 designated A, as shown.

The circular plate 5 is provided with parallel flanges 8 which are formed by striking them out from the plate 5 and leaving a longitudinal slot or opening 9 through which the piston rod B extends and permits free play of the latter.

In order to hold the device in place there is provided a split ring 10 which is received within the annular flange 6 and terminates in a pair of spaced inwardly directed parallel eyes 11 through which an adjusting

bolt 12 extends. This adjusting bolt 12 is threaded throughout its entire length to receive pairs of jamb nuts 13 disposed upon opposite sides of the eyes and retain the 60 same in adjusted position. It will be observed that upon adjusting the nuts 11 the ring may be expanded sufficiently to hold the flange 6 against the walls of the engine piston. It will be observed that the device 65 prevents the passage of lubricant through the piston and hence through the wrist pin bearing and is thereby prevented from entering the engine cylinder above the piston and consequently fouling the spark plug. 70

While I have shown and described the preferred embodiment of the invention, I desire to have it understood that such changes may be made in the form, construction and arrangement of parts as will not depart from the spirit of the invention or the scope of the subjoined claims.

What is claimed is:

1. The combination with an internal combustion engine piston, of a plate closing the lower end thereof, means for retaining the plate in the piston, the plate being provided with a longitudinal slot through which the piston rod passes, and flanges depending from the plate and disposed upon opposite sides of the opening and piston rod.

2. An attachment for an internal combustion engine piston comprising a circular plate adapted to be positioned in the piston, an annular flange thereon in contact with the piston walls, a split ring received in the flange and adapted to resiliently hold the same against the walls of the piston, laterally disposed parallel ears on the ends of the split band and adjusting means engaging the 95 eyes.

3. An attachment for an internal combustion engine piston comprising a circular plate to be positioned within the lower end of the piston and provided with a longitudinal slot through which the piston rod is adapted to pass, depending parallel flanges formed on the plate and at opposite sides of the opening, a split band engaging the flange, laterally and inwardly directed eyes carried 100 by the band, a pivoted element passing through the eyes and jamb nuts engaged on the pivoted element and disposed on opposite sides of each of the eyes.

In testimony whereof I affix my signature. 110

CHARLES W. CRAM.
